UNITED STATES PATENT OFFICE.

PAUL S. HALL, OF AUSTIN, MINNESOTA, ASSIGNOR OF ONE-HALF TO GUSTAV J. VOSS,
OF AUSTIN, MINNESOTA.

ELECTRIC-LIGHT SOCKET AND BULB BASE.

Application filed September 22, 1926. Serial No. 137,095.

This invention relates to electric light sockets for lamp bulbs, and contemplates the provision of means for locking the bulb in the socket, and thereby prevent theft of 5 the bulbs, or loosening of the latter when subject to vibration under any circumstances.

In carrying out the invention I contemplate the use of a resilient locking finger arranged within the socket, and adapted to 10 operate with a shoulder formed on the base of the lamp bulb, so that when the latter is screwed into the socket, it can not be removed therefrom without destroying the bulb.

The nature and advantages of the invention 15 will be better understood when the following detail description is read in connection with the accompanying drawing, the invention residing in the construction, combination and arrangement of parts as claimed.

20 In the drawing forming part of this application like numerals of reference indicate similar parts in the several views and wherein:

Figure 1 is a sectional view showing how 25 the bulb is locked within the socket.

Figure 2 is a sectional view showing the arrangement of the locking finger within the socket.

30 Figure 3 is an end view of the bulb showing the shoulder formed in the base thereof.

Referring to the drawing in detail 10 represents an electric light socket of ordinary well known construction in which is arranged 35 a curved resilient locking finger 11. The finger is secured to the base of the socket at one end thereof as at 12, while the other end of the finger is curved outwardly and downwardly to lie in a path of the base 13 of an

electric light bulb 14, when the latter is being screwed into the socket. The base of this 40 bulb is formed with a beveled or inclined surface 15 at one end of which is arranged a shoulder 16, and when the bulb is screwed home within the socket, the free end of the locking finger rests upon the inclined surface 45 15, and bears against the shoulder 16 in a manner to prevent the bulb from being removed or loosened within the socket when subjected to vibration. The only way in which the bulb can be removed is by breaking 50 the latter and subsequently making use of suitable instruments to force the finger 11 away from the shoulder.

While it is believed that from the foregoing description, the nature and advantages 55 of the invention will be readily apparent, I desire to have it understood, that I do not limit myself to what is herein shown and described and that such changes may be resort- 60 ed to when desired as fall within the scope of what is claimed.

What is claimed is:

The combination with an electric light socket, a lamp bulb base received by said socket and having a peripheral inclined surface 65 and a vertical shoulder formed thereon, and a horizontally disposed flat resilient finger terminally secured to the base of said socket and spaced therefrom, said finger being twisted 70 at a point in its length to position its free end tangentially to the bulb base and contact said shoulder for locking the bulb against movement within the socket.

In testimony whereof I affix my signature.

PAUL S. HALL.
